UNITED STATES PATENT OFFICE.

CHARLES APPLEHANS, OF NORWICH, CONNECTICUT, ASSIGNOR TO JAMES O'CONNELL, HERMINE APPELHANS, HARRIET APPELHANS, VALESKA APPELHANS, AND JOHN H. BARNES, OF SAME PLACE.

BEER-DRAWING APPARATUS.

SPECIFICATION forming part of Letters Patent No. 678,771, dated July 16, 1901.

Application filed October 25, 1900. Serial No. 34,316. (No model.)

To all whom it may concern:

Be it known that I, CHARLES APPLEHANS, a citizen of the United States, residing at Norwich, in the county of New London and State 5 of Connecticut, have invented certain new and useful Improvements in Beer-Drawing Apparatus, of which the following is a full, clear, and exact description.

This invention relates to apparatus for 10 drawing beer and other liquids from the barrel or receptacle containing the same; and the particular object of my invention is to improve that class of apparatus to the end that such barrels may be readily tapped with 15 out the aid of special tools and without the use of destructible plugs or bungs that have to be renewed upon the refilling of the barrel.

To assist in the explanation of my invention I have provided the accompanying sheet 20 of drawings, illustrating the same, as follows.

Figure 1 shows in central vertical section a beer-keg having connected therewith a beer-drawing device embodying my improvements. Fig. 2 is an enlarged central vertical section view of the bung and of a portion of the faucet. Fig. 3 is plan view of the bung. Fig. 4 is a view of the lower end of the bung with the plate *f* removed to disclose the valve-disk. In this view the valve is illustrated in 25 full lines as closed and in dotted lines as swung half open. In Fig. 5 I have shown a similar view with the valve in its wide-open position. Fig. 6 is a view of that end of the faucet that coacts with the bung. Fig. 7 is 30 a cross-sectional view taken on line 7-7 of Fig. 2.

Referring to the drawings, the letter *a* indicates the keg; *b*, a complete bung of my improved construction mounted in the head 40 of the keg; *c*, a faucet of peculiar construction removably connected with the bung, and *d* a tube by means of which the beer may be drawn from the bottom of the barrel. I will first describe the bung *b*, as the said 45 bung includes a peculiar valve that forms one of the essential features of my invention.

The bung proper consists of a metallic bushing *b'*, that is screw-threaded externally, as at *b''*, in order that it may be screwed into

the barrel-head. Bushing *b'* is counterbored 50 from its lower end to receive a loosely-fitting shell *b³*, whose lower end is flush with the end of bushing *b'* when the parts are assembled. Projecting inward from the shell *b³* near its upper end are studs *b⁴*, and extending downward from the lower end of the shell is a stud *b⁵*, which latter stud is provided to transmit motion to a valve which I will now describe. The valve *e* is of circular-washer form, having an opening *e'* that 55 is located off from the center and is somewhat larger than the diameter of the pipe *d*, and said valve is pivoted on a bolt *e²* in such manner that it (the valve) may be swung to one side, as indicated by dotted lines in Figs. 4 and 5, to open a central passage through the bung. Outside the valve *e* is a centrally-perforated washer *f*, that is fixedly secured 60 to the bushing *b'* by the described bolt *e²* and a similar bolt *e³*, the valve-disk being provided with an elongated slot *e⁴*, through which the bolt *e²* passes, the slot *e⁴* being of sufficient 65 length to permit the swinging of the valve during the opening and closing of the latter, as I shall explain more in detail later on. 70

The fixed washer *f* serves to hold the movable valve-disk in close engagement with the end of the bung-bushing *b'*, thus insuring a liquid-tight joint; but the valve is not held so tightly as to prevent it from being swung 80 laterally with comparative ease. The stud *b⁵*, which I have already described, lies in a hole *e⁵* in the valve *e*, and it will now be understood that when the inner shell or bushing *b³* is partially rotated within the bung-bushing *b'* the stud *b⁵* will operate to swing the valve-disk *e* to one side, as seen in Figs. 4 and 5, thus bringing the hole *e'* into coincidence with the central opening in the complete bung and providing an unobstructed opening 90 throughout said bung through which the pipe *d* may be readily passed.

I desire to call particular attention to the way in which the valve-disk *e* is supported and guided by the bolts *e²* *e³*. I have found 95 in practice that the opening *e'* in the valve-disk cannot be brought into coincidence with the central opening in the bung except by

combining with the described swinging movement of the valve-disk a "floating" motion in a limited degree, for the reason that the stud b^3 , which controls the swinging movement of the valve-disk, travels in an arc of the circular path described by the bushing b^3 , and consequently the valve-disk is caused to describe the same circular movement, and in order to permit such movement I am obliged to elongate the opening e^6 , through which the stud e^2 passes, as is best seen in Figs. 4 and 5 of the drawings. This arrangement of stud and slot permits a limited lateral or floating movement of the valve-disk, although the center of its movement is approximately the center of stud e^2 . In Figs. 4 and 5 I have illustrated, respectively, the two extremes of movement of the valve-disk, and in dotted lines in Fig. 4 I have indicated its median position.

Having described my improved valve, I will proceed to describe the means by which I rotate the bushing b^3 in order to swing the valve-disk to open and close the valve. The bung-bushing b^1 is formed at its upper end with oppositely-arranged radial slots $g^1 g^1$, that lead into an undercut annular channel g^2 , and the faucet c is formed with oppositely-disposed radial lugs $c^1 c^2$, that are adapted to enter the slots $g^1 g^1$ and lock in the said annular channel g^2 upon giving to the faucet a partial rotation after entering it in the bung. The end of the faucet is extended and is slotted transversely, as at c^3 , the said slit being of a size adapted to slip over the studs b^4 when the faucet end is entered in the bung, it being assumed that the valve is closed when the faucet is thus entered in the bung. When the faucet is partially rotated to lock its lugs $c^1 c^2$ in the annular channel g^2 , the slotted end c^3 simultaneously rotates the bushing b^3 and opens the valve. It will thus be seen that the opening of the valve is dependent upon the locking of the faucet in the bung and, *per contra*, the removal of the faucet from the bung will simultaneously and automatically close the valve, thus making it impossible to open the

valve except when the faucet is in its operative position in the bung or to separate the faucet and bung without simultaneously closing the valve, and thus shutting off the escape of the liquid. The body of the faucet c has a straightway opening through it that registers with the opening in the bung when the parts are assembled in the manner described, and on the outer end of the faucet is a stuffing-box c^4 , that is adapted to receive the pipe d , as seen in Fig. 1. Connected with the opening in the faucet is a pipe h , through which air may be forced into the faucet and thence into the barrel. The pipe d has connected therewith a cock d' and a pipe d^2 , through which the liquid is delivered at any desired distant point.

When the various elements of my improved beer-drawing apparatus are properly assembled, it will be understood that a current of air introduced through pipe h will force the contents of the barrel to seek an outlet, which outlet is found only through the pipe d , the overflowing and cutting off of the liquid being controlled by opening or closing the cock d' .

My described improvement is of very simple construction, is easily applied to bungs and faucets of the kinds most commonly used, and serves to greatly increase the efficiency of beer-drawing apparatus without increasing materially the cost thereof.

Having thus described my invention, I claim—

In combination, in a bung, an outer shell, a revoluble bushing in said shell, bolts projecting from the end of said shell, a valve-disk formed with elongated slots $e^4 e^6$ that engage the said bolts whereby a floating movement of the valve-disk is obtainable as set forth, and means for swinging the said valve-disk on its supports.

Signed at Norwich, Connecticut, this 15th day of October, 1900.

CHARLES APPLEIANS.
